UNITED STATES PATENT OFFICE.

WILLIAM FRANKLIN JAYNES, OF EVANSVILLE, INDIANA.

CHANNEL-CUTTER FOR SOLE-STITCHING MACHINES.

1,301,269.

Specification of Letters Patent.

Patented Apr. 22, 1919.

Application filed October 29, 1917. Serial No. 199,119.

To all whom it may concern:

Be it known that I, WILLIAM F. JAYNES, a citizen of the United States, residing at Evansville, in the county of Vanderburgh and State of Indiana, have invented certain new and useful Improvements in Channel-Cutters for Sole-Stitching Machines; and I do declare the following to be a full, clear, and exact description of the invention, such as will enable others skilled in the art to which it appertains to make and use the same.

My invention has for its object to provide an extremely simple and inexpensive, yet a highly efficient and durable channel cutter which may be attached to the well known forms of sewing machines for stitching shoe soles, the device being operated by the usual feed dog and being so positioned as to cut a channel to receive the stitches formed by the needle and the usual stitching mechanism.

With the foregoing general object in view, the invention resides in the novel features of construction and unique combinations of parts to be hereinafter fully described and claimed, the descriptive matter being supplemented by the accompanying drawings which form a part of this specification and

in which:—

Figure 1 is a side elevation, partly in section, showing the application of my invention to a sole stitching machine;

Fig. 2 is a horizontal section cut above the work support; and

Fig. 3 is a detail perspective view of the channel cutter and its operating yoke.

In the drawings above briefly described, the numeral 1 designates the work support of a common type of sole stitching machine, 2 designates the presser foot, 3 the needle, and 4 the usual proceeding and receding feed dog which advances the sole 5 when the needle 3 is raised. The presser foot 2 is preferably provided with a roller 6 traveling upon the work, and with an eye 7 through which the needle 3 extends. It will be understood, however, that the construction of the machine constitutes no part of my invention, but that the features above set forth are shown only for the sake of illustrating the improved device applied to the machine. This device is intended principally for use upon the Singer machine, No. 45, but it is to be understood that it may also

be employed on numerous other types of machines.

The work support 1 is provided with a groove 8 in its upper side, said groove opening through the edge of said support and extending in a direction parallel with the line of movement of the feed dog 4. Within this groove, the upper horizontal arm 9 of a substantially C-shaped yoke 10 is slidably positioned, whereas the other arm 11 of said yoke, which I term the operating arm is positioned under the support 1 and abuts the dog 4 so that the receding strokes of this dog will move the entire yoke 10 so as to move the channel cutter 12 along the lower side of the sole 5, said cutter being in the form of a short upstanding blade carried by the free end of the arm 9. The return movement of the dog 4 and the consequent action of the yoke 11 and the cutter 12, take place while the needle 3 passes through the sole 5 and holds the latter against possible movement with these parts. It will thus be observed that the blade 12 will form a shallow channel 13 in the lower side of the sole to receive the stitching formed by the needle and the other well known stitching mechanism.

To constrain the yoke 10 to follow the dog 4 upon the proceeding or working strokes thereof, a spring 14 bears against the vertical portion 15 of said yoke, said spring being preferably secured to the edge of the work support 1 by a screw or the like 16.

From the foregoing, taken in connection with the accompanying drawings, it will be obvious that although my invention is of extremely simple and inexpensive nature, and may be quickly and easily applied to sole stitching machines, the device will be highly efficient for the purposes intended. Since probably the best results are obtained from the exact features shown and described, these features are preferably employed, but I wish it understood that within the scope of the invention as claimed, numerous minor changes may well be made.

I claim:—

1. The combination with a sole stitching machine including a horizontal work support and a proceeding and receding feed dog below said support for feeding the work when the needle is raised, and a cutter operating yoke having parallel arms straddling

said work support, the upper arm of said yoke having a channel cutter, and the lower arm of said yoke being operatively associated with said feed dog for moving said yoke to operate the cutter upon the receding strokes of said dog.

2. The combination of a sole stitching machine including a work support and a proceeding and receding dog below said support for feeding the work when the needle is raised, said support having in its upper side a groove extending through its edge, a cutter-operating yoke having parallel arms straddling said edge, the upper arm sliding in said groove and having a channel cutter, the lower arm of said yoke being operatively associated with said feed dog for moving said yoke to operate the cutter upon the receding strokes of said dog.
3. The combination of a sole stitching machine including a work support and a proceeding and receding dog below said support for feeding the work when the needle is raised, said support having in its upper side a groove extending through its edge, a cutter-operating yoke having parallel arms straddling said edge, the upper arm sliding in said groove and having a channel

cutter, the lower arm of said yoke abutting said feed dog, whereby the receding strokes of said dog will shift the yoke to operate the cutter, and spring means for constraining said yoke to follow said dog on its proceeding strokes.

4. As an article of manufacture, a channel cutting attachment for sole stitching machines comprising an arm adapted to slide horizontally in a groove in the top of the work support of the machine, one end of said arm having an upstanding channel cutter, a yoke bar depending from and integral with the other end of said arm, and an operating arm parallel to said first named arm and integral with one end of said yoke bar, said operating arm being adapted to slide horizontally beneath the aforesaid work support and to abut and receive its movement from the feed dog of the machine.

In testimony whereof I have hereunto set my hand in the presence of two subscribing witnesses.

WILLIAM FRANKLIN JAYNES.
